UNITED STATES PATENT OFFICE

2,663,262

CENTRIFUGAL PUMP WITH SEALING DEVICE

Elof Malmvik and Edwin Dunér, Jonkoping, Sweden, assignors to Jonkopings Mekaniska Werkstads Aktiebolag, Jonkoping, Sweden, a joint-stock company

Application February 19, 1948, Serial No. 9,465
In Sweden December 16, 1942

Section 1, Public Law 690, August 8, 1946
Patent expires December 16, 1962

3 Claims. (Cl. 103—111)

1

This invention relates to a centrifugal pump with a sealing device and is especially intended for use in connection with pumping of corrosive liquids, such as waste liquid from the cellulose industry and liquids containing, for instance, sulphuric, hydrochloric or nitric acid, ammonia, chlorine or the like. Such liquids attack chemically and mechanically the stuffing boxes in the pumps, especially as the liquids often have a high temperature, and the pumps, therefore, have to be repaired frequently.

One object of the invention is to secure the sealing between the pump shaft and the casing by means of a hydraulic seal of a simple but efficient construction.

An other object is to provide a sealing device of such a construction which requires no or only very little attendance.

A further object is to reduce the power consumption in the hydraulic seal.

A still further object is to provide a sealing device adapted to resist pressure as well as vacuum.

These and other features, characteristics and advantages of the present invention will become apparent from the following disclosures taken in conjunction with the accompanying drawing, in which:

Figure 1 is an axial section of a centrifugal pump with an appendant sealing device according to one form of the invention.

Figure 2 is an axial section on an enlarged scale of another form of the sealing device, and

Figure 3 is a similar axial section of a third form of the sealing device.

In the pump shown in Figure 1 the pump shaft 1 is mounted in a bearing 2, shown only in part, and the lower end of the pump shaft is provided with a runner 3. The pump casing 4 is designed in such a way that the liquid to be propelled flows through an inlet conduit 5 into an inlet chamber 6 situated at the same side of the runner as the sealing device, the liquid flowing from said chamber through a coaxial opening 7 into the very runner chamber 8, wherein it is being impelled in known manner towards the outlet 9. The pump shaft 1 which would be attacked by the corrosive liquid if brought into contact therewith, is covered by sleeves 10, 11 of resistant material which have been slid, one after another, onto the shaft over the free end thereof, said sleeves serving also as distance pieces for keeping the sealing impeller 12 in correct position axially, which impeller is positioned between the inlet chamber 6 and the

2

bearing arrangement 2. This position of the sealing device and the inlet chamber implies that a seal must be provided only for the over-pressure or vacuum arising at the suction side of the pump, which pressure, as a rule, is much lower than at the pressure side of the pump, whereby the power consumption in the sealing device is correspondingly reduced.

The sealing impeller which consists of a disc 14, projecting from the nave 13, and a cylindrical rim or flange 15 projecting axially from the edge of said disc, is provided on both sides with blades or vanes, the lower blades 16 facing the inlet chamber 6 extending inwardly from the rim 15 to a certain distance from the shaft, or the sleeve 10 surrounding the same, whereas the upper blades 17 facing the bearing arrangement 2 extend from the rim 15 to the nave 13 of the sealing impeller. By means of a key 18 the sealing impeller is keyed to the shaft 1, and it rotates in a chamber 19 separated from the inlet chamber by means of a transverse partition wall 20 carrying a central, nave-shaped portion 21 surrounding the sleeve 10 with a clearance just sufficient to permit a frictionless rotation of said sleeve together with the pump shaft 1, thereby allowing a communication between the sealing impeller and the pump chamber 8. The nave-shaped portion extends somewhat above the lower edge of the blades 16 of the sealing impeller. The chamber 19 will thus constitute a fluid pocket containing a sealing fluid which may be constituted by the liquid conveyed by the pump, and in the pocket the sealing wheel is submerged with the lower portion of its rim 15 and the blades 16. Towards the bearing means 2 the chamber 19 is bounded by a partition 22 joining the sleeve 11 with a slight clearance. On the opposite side of this partition there is a further chamber 23 with an outlet 24 for liquid possibly leaking through in the moment as the pump is started. It is understood, however, that the pump should be provided with a valve in the suction pipe and another valve in the pressure system to be closed when the pump is at rest.

The operation of the device is as follows. When the pump is to be started, the sealing chamber 19 is or should be at least partly filled with the pump liquid or another liquid. By the use of the annular pocket it is always assured that the necessary quantity of sealing liquid is at hand. As the shaft begins to rotate all sealing liquid in the chamber 19 is caused to rotate by the blades and thrown towards the periphery

by the centrifugal force thereby forming between the sealing wheel and the casing a sealing ring which keeps the connection between the pump chamber 6 and the chamber 23 leading to the open air entirely closed. The valves in the suction pipe and thereafter in the pressure system are now opened.

It is now assumed that a certain vacuum exists in the inlet chamber 6. The fluid in the chamber 19 will then be forced more or less to the portion of the chamber occupied by the lower blades until the suction action is balanced by the pumping action of the blades. If, on the other hand, the pump is connected on the suction side with a container, in which the liquid level in the beginning causes a certain overpressure in the inlet chamber 6, then the sealing liquid rises in the chamber 19 and flows over the upper blades. As these have a greater radial extension than the lower blades they can overcome the action of the lower blades and also exert an additional pressure for balancing the overpressure in the inlet chamber. As an example it may be mentioned that such a sealing wheel having 7½" diameter of the upper blades and 4½" diameter of the lower blades may seal for a suction of 11 lbs./sq. in. up to an overpressure in the inlet chamber of 43 lbs./sq. in. The liquid level in the container may thus vary between wide limits without causing any leakage in the hydraulic seal.

For pumps operating under still higher overpressure in the inlet chamber 6 the embodiments shown in Figure 2 or 3 may be used.

Figure 2 shows a construction of a sealing wheel, wherein the disc 14 and the blades 17' provided thereon have been extended radially, whereas the lower blades have maintained their form and extension shown in Figure 1 or, rather have been reduced in size. By maintaining only the lower portion of the rim 15 bounding the blades 16, and extending the disc 14 beyond said rim, it is possible to obtain a considerably increased length of the upper blades 17' counteracting overpressure.

In the embodiment shown in Figure 3 the sealing wheel comprises two radially disposed discs, a lower disc 14 which, as in the embodiment according to Figures 1 and 2, is provided with upper blades 17" and lower blades 16, and an upper disc 25 provided with blades 26 on its upper side only and arranged to rotate in a chamber 27 separated by means of a radial partition 28 from the fluid pocket chamber 19 previously described. If, in a pump provided with such a sealing device, the pressure in the inlet chamber 6 increases to such an extent that the single sealing wheel 14 is not sufficient to prevent escape of the liquid, the said liquid flows into the second chamber 21 constituting, together with the disc 25, a second fluid seal, the lower branch of which is not acted upon by blades and, consequently, not very effectively thrown outwardly in the direction of action of the overpressure prevailing in the inlet chamber, the upper branch of which, however, is operated upon by a number of blades of comparatively large radial extent and which are adapted to create a centrifugal force constituting in this branch a substantial counteraction against the pressure acting to drive the liquid through the sealing device.

We claim:

1. In a vertical centrifugal pump, a pump shaft, a runner mounted on the lower end of said pump shaft, a pump chamber surrounding said runner

and being closed downwardly, an upper inlet to said pump chamber, a sealing chamber around the pump shaft above said inlet, said sealing chamber having a bottom with a short upright ring-shaped inner wall so as to form a pocket for receiving and retaining sufficient pump liquid to form a sealing ring of pump liquid, said bottom of said sealing chamber having an opening for the pump shaft which opening is larger than said shaft so as to provide a ring-shaped space around the pump shaft to allow admittance of pump liquid from said inlet to the pocket in said sealing chamber, and a sealing impeller mounted on the pump shaft in said sealing chamber and comprising a horizontal disc, a series of lower blades on the lower surface of said disc, said lower blades having free inner edges so as to leave a space occupied by said upright wall extending into said pocket, and a series of upper blades on the upper surface of said disc, said upper blades having a greater radial extension than said lower blades.

2. In a vertical centrifugal pump, a pump shaft, a runner mounted on the lower end of said pump shaft, a pump chamber surrounding said runner and being closed downwardly, an upper inlet to said pump chamber, a sealing chamber around the pump shaft above said inlet, said sealing chamber having a bottom with a short upright inner wall so as to form a pocket for receiving and retaining sufficient pump liquid to form a sealing ring of pump liquid, said bottom of said sealing chamber having an opening for the pump shaft which opening is larger than said shaft so as to provide a ring-shaped space around the pump shaft to allow admittance of pump liquid from said inlet to the pocket in said sealing chamber, and a sealing impeller mounted on the pump shaft in said sealing chamber and comprising a horizontal disc having a downwardly extending circular flange, a series of lower blades on the lower surface of said disc, said lower blades having free inner edges so as to leave a space occupied by said upright wall extending into said pocket and being united at their outer ends with said flange, and a series of upper blades on the upper surface of said disc, said upper blades having a greater radial extension than said lower blades.

3. In a vertical centrifugal pump, a pump shaft, a runner mounted on the lower end of said pump shaft, a pump chamber surrounding said runner and being closed downwardly, an upper inlet to said pump chamber, a sealing chamber around the pump shaft above said inlet, said sealing chamber having a bottom with a short upright inner wall so as to form a pocket for receiving and retaining sufficient pump liquid to form a sealing ring of pump liquid, said bottom of said sealing chamber having an opening for the pump shaft which opening is larger than said shaft so as to provide a ring-shaped space around the pump shaft to allow admittance of pump liquid from said inlet to the pocket in said sealing chamber, and a sealing impeller mounted on the pump shaft in said sealing chamber and comprising a horizontal disc having a downwardly extending circular flange, an upwardly extending flange, a series of lower blades on the lower surface of said disc, said lower blades having free inner edges so as to leave a space occupied by said upright wall extending into said pocket and being united at their outer ends with said downwardly extending flange, and a series of upper blades on the upper surface of said disc, said upper blades

having a greater radial extension than said lower blades and being united at their outer ends with said upwardly extending flange.
